UNITED STATES PATENT OFFICE

LANCE ERNEST BOOTH, OF ROSELLE, NEW JERSEY, ASSIGNOR TO GOLD DUST CORPORATION, OF NEW YORK, N. Y., A CORPORATION OF NEW JERSEY

DESIGN FOR A CUT-OUT FOR DOLLS

Application filed January 25, 1933. Serial No. 46,972. Term of patent 14 years.

To all whom it may concern:

Be it known that LANCE ERNEST BOOTH, a citizen of the United States of America, and residing at Roselle, New Jersey, has invented a new, original, and ornamental Design for a Cut-Out for Dolls, of which the following is a specification, reference being had to the accompanying drawing, forming part thereof,

The figure is a plan view of a cut-out for dolls showing my new design.

I claim:

The ornamental design for a cut-out for dolls as shown.

Dated at New York, N. Y., this 11th day of January, 1933.

LANCE ERNEST BOOTH.
